Primary Examiner — Melanie H Tung(74) *Attorney, Agent, or Firm* — Banner & Witcoff, Ltd.(57) **CLAIM**

The ornamental design for a display screen with graphical user interface, as shown and described.

DESCRIPTION

The FIGURE is a front view of a display screen with graphical user interface showing the new design.

The broken line showing of the display screen and the remainder of the graphical user interface is for environmental purposes only and forms no part of the claimed design.

1 Claim, 1 Drawing Sheet
